United States Patent Office

Des. 212,843
Patented Dec. 3, 1968

212,843

CLOSURE CAP OR THE LIKE

Alexander W. Hart and Daniel D. Acton, Lancaster, Ohio, assignors to Anchor Hocking Glass Corporation, Lancaster, Ohio, a corporation of Delaware

Filed Jan. 23, 1968, Ser. No. 10,278

Term of patent 14 years

(Cl. D9—267)

FIG. 1 is a perspective view of a closure cap or the like, showing our new design;

FIG. 2 is a top plan view thereof; and

FIG. 3 is a side elevational view thereof.

We claim:

The ornamental design for a closure cap or the like, substantially as shown.
